UNITED STATES PATENT OFFICE.

CHARLES E. LINK, OF REMINGTON, OHIO.

DECARBONIZER SPRAYER.

Application filed November 17, 1923. Serial No. 675,432.

To all whom it may concern:

Be it known that I, CHARLES E. LINK, a citizen of the United States, residing at Remington, in the county of Hamilton and 5 State of Ohio, have invented new and useful Improvements in Decarbonizer Spray-
ers, of which the following is a specifi-
cation.

This invention relates to a sprayer de-
vice, the general object of the invention
being to provide means for spraying a car-
bon remover into the combustion chamber
of an internal combustion motor, so as to
reach all parts of the walls of the chamber
15 with the liquid, to soften the carbon there-
on with the minimum amount of fluid.

Another object of the invention is to so
form the sprayer that the fluid will be
mixed with a large amount of air and that
20 the fluid will be forced from the device in
small quantities so that the device will have
to be operated for a considerable amount
of time in order to discharge the fluid
therein, thus avoiding waste of the fluid by
25 ejecting too much fluid on each stroke of
the sprayer.

A further object of the invention is to
provide a number of nozzles so that the
device can be used on different types of
30 motors and on motors, the spark plug holes
of which are difficult of access.

This invention also consists in certain
other features of construction and in the
combination and arrangement of the sev-
35 eral parts, to be hereinafter fully described,
illustrated in the accompanying drawings
and specifically pointed out in the appended
claims.

In describing the invention in detail,
40 reference will be had to the accompanying
drawings wherein like characters denote
like or corresponding parts throughout the
several views, and in which:—

Figure 1 is a sectional view through a
45 cylinder of a motor showing how the in-
vention is used.

Figure 2 is a longitudinal sectional view
through the sprayer device.

Figure 3 is a longitudinal sectional view
50 showing the sprayer provided with an at-
tachment for use on motors, the openings
of which are difficult of access.

Figure 4 is a transverse sectional view
55 through the perforated part of the tube
of this attachment.

Figure 5 is a view, with parts in section,
of this tube.

Figure 6 is a view of a modified form of
tube.

Figure 7 is a view of a form of nozzle 60
which may be used with the device.

Figure 8 is a view of another form of
nozzle.

Figure 9 is a sectional view showing a
centrally arranged retainer tube and an- 65
other form of nozzle.

Figure 10 is a sectional view of an ex-
tension pipe.

Figure 11 is a view of a nozzle 9.

In these views 1 indicates the cylinder 70
of the sprayer pump, 2 the piston thereof
and 3 the piston rod which is provided with
the handle 4. The piston is double acting
so that on the up stroke it will produce a
vacuum in the lower end of the cylinder 75
and on the down stroke it will act to force
the air and fluid through the tube 5. This
tube acts as a retainer for the fluid drawn
into the cylinder on the up stroke of the
piston as it extends an appreciable distance 80
into the lower end of the cylinder to form
a trap for the fluid. If too much liquid is
drawn into the cylinder so that the level
thereof is above the upper end of the tube,
this surplus liquid will flow out of the tube 85
until the level is below the top of the tube.

A very small hole 6 is formed in the tube
just above the lower end of the cylinder
so that some of the liquid will be forced
into the tube through this hole on the 90
down stroke of the piston. This hole is
so small, however, that but a small quantity
of liquid will be discharged on each down
stroke of the piston. I prefer to make the

bottom of the piston in the form of a screw 95
cap 7 through which the tube passes and
to offset the tube from the center of the
cap. I also bend the inner end of the tube
as shown at 8 so that the tube will retain
a certain amount of liquid in the cylinder 100
even though the cylinder is held horizontal-
ly or at an incline. The hole is made in
the tube on the opposite side from the bend
so that practically all the liquid in the cyl-
inder can be forced through the hole for 105
operating the device and while held in a
horizontal or inclined position. However,
when the device is used on motors, the cyl-
inders of which are vertical, the upper end

of the tube may be straight, as shown at 110
115

5' in Figure 9 and said tube may pass through the center of the cap 7', as shown in this figure. The bent tube eccentrically arranged, is designed for use where the 5 sprayer is used on motors, the cylinders of which are horizontally or inclinedly arranged, and on motors in which the spark plug holes are difficult of access.

A nozzle 9 is connected with the retainer 10 tube 5 by the coupling 10 and I may provide a plurality of nozzles for use with the sprayer so that the proper kind of nozzle can be used with the device. The drawings show various kinds of nozzles which may 15 be used with the device, though, it will, of course, be understood, that any desired type of nozzle can be used with the device. Figures 1, 2, 3 and 9 show nozzles which will direct the stream upwardly while Figure 7 20 shows a nozzle which will direct the stream at practically rightangles from the device and Figure 8 shows a nozzle for directing the stream downwardly at an angle. Of course, the nozzle most suitable for the 25 motor upon which the device is being used, will be attached to the device. In Figure 9 the nozzle is screwed directly upon the tube 5' while in the other figures the nozzle is intended to be connected with the tube by 30 a coupling, such as shown at 10.

When necessary or desirable, an extension pipe 11, shown in Figure 10, may be connected with the retainer tube and have the nozzle attached thereto.

35 On motors which have the gas tanks arranged above their cylinder heads, which makes the spark plug holes difficult of access, an attachment such as shown at A in Figure 3 is used with the device. This 40 attachment comprises a body 12 having a chamber 13 therein and through which passes a tube 14 which is rotatably mounted in the body and which is held fluid-tight therein by means of the glands 15. That 45 portion of the tube located in the chamber is provided with perforations 16, one of which is arranged at the bottom of the chamber and acts as a drain for the chamber. This tube may be formed with slots 50 17 as well as the perforations, as shown in Figures 5 and 6. In this case the drain hole 16' is arranged quite a distance below the other holes. The body is provided with a tubular part 18 which has its lower end 55 in communication with the bottom of the chamber and its outer end threaded to receive the coupling 10 on the retainer tube 5 of the device. The tube 14 is provided with a handle 19 so that it can be rotated 60 and a nozzle of any desired type is connected with the lower end of the tube by the coupling 20.

With this attachment, the Ford type of tractor and similar motors, can be sprayed with this device by inserting the nozzle on

the tube 14 of the attachment in the spark plug hole and then operating the plunger of the spray pump to force liquid and air from the pump into the chamber of the attachment from which the mixture will 70 pass through the holes in the tube 14, through the tube and out of the nozzle. By turning the tube by means of the handle 19 all parts of the combustion chamber 75 will be sprayed.

This attachment is also useful in spraying motors of the horizontal and inclined types, as the attachment can be adjusted with respect to the spray pump by means of the coupling 10 so as to cause the spray 80 to reach all parts of the walls of the combustion chamber.

From the foregoing, it will be seen that the carbon remover is drawn into the device by inserting the nozzle or the end of 85 the retainer tube in the liquid and then pulling the piston upwardly to suck the liquid into the cylinder. As before stated, the extension of the retainer tube holds a certain amount of liquid in the cylinder 90 and when the piston is operated a small amount of this liquid is forced through the hole 6 in the tube and mixes with the air forced through the tube by the piston and this mixture is sprayed upon the walls of 95 the combustion chamber so as to soften the carbon thereon. By moving the device, all parts of the combustion chamber are sprayed and due to the small quantity of fluid ejected on each stroke of the piston, 100 a minimum amount of fluid is used for treating each cylinder.

While the invention is shown as a pump sprayer, it will, of course, be understood that it may be used on other types of sprayers. For instance, it may be used on the type where a rubber bulb is utilized for providing the pressure necessary to force the liquid from the container. The essential part of the invention comprises the retainer tube and the small hole therein for causing the fluid to pass from the device in small quantities.

The device will eject the mixture of air and fluid in the form of a mist, so that 115 all the walls of the combustion chamber will be coated with the mixture.

Any kind of a liquid carbon remover can be used with the device. I have found that denatured alcohol is very effective as a carbon remover and the best time to spray the cylinder is at night after the motor has partially cooled off. The remover will act upon the carbon during the night so that when the motor is started up in the morning, the soft carbon will be blown out of the motor. The motor should be sprayed quite frequently and when this is done, the combustion chambers of the motor are kept 125 free of carbon and the expensive job of 130

scraping carbon from the cylinders is eliminated.

It is thought from the foregoing description that the advantages and novel features 5 of my invention will be readily apparent.

I desire it to be understood that I may make changes in the construction and in the combination and arrangement of the several parts, provided that such changes fall within 10 in the scope of the appended claims.

What I claim is:—

1. A decarbonizer sprayer comprising a sprayer device, a retainer tube extending into the same and having its open inner end spaced above the bottom of the device and acting to hold a certain amount of decarbonizer in the device and a small vent in said tube just above the bottom of the device. 15

2. A decarbonizer sprayer comprising a sprayer device, a retainer tube extending into the same and having its open inner end spaced above the bottom of the device and acting to hold a certain amount of decarbonizer therein, said tube having a small 20 vent just above the bottom of the device and a nozzle detachably connected with the tube.

3. A decarbonizer sprayer comprising a sprayer device, a retainer tube extending into the same and acting to hold a certain 30 amount of decarbonizer therein, said tube having a small vent just above the bottom of the device, the inner end of the tube being curved and said tube being eccentrically arranged in the device.

35 4. A decarbonizer sprayer comprising a cylinder, a piston therein, means for reciprocating the piston, a retainer tube passing through the bottom of the cylinder and having a small vent just above the bottom, the

upper end of the tube being bent and means 40 for connecting a nozzle with the outer end of the tube.

5. A decarbonizer sprayer comprising a cylinder, a piston therein, a combined rod and handle connected with the piston, a cap 45 closing the lower end of the cylinder, a tube passing through the cap and projecting into the cylinder, with its open inner end located an appreciable distance above the cap, said tube having a small vent hole 50 therein just above the inner face of the cap.

6. A decarbonizer sprayer comprising a cylinder, a piston therein, a combined rod and handle connected with the piston, a cap 55 closing the lower end of the cylinder, a tube passing through the cap to one side of the center thereof and having its inner end projecting into the cylinder and curved, said tube having a small vent hole therein just 60 above the inner face of the cap.

7. A decarbonizer sprayer comprising a cylinder, a piston therein, a piston rod connected with the piston, a retainer tube passing through the bottom of the cylinder and 65 projecting into the cylinder, said tube having a small vent hole therein adjacent the bottom of the cylinder and an attachment connected with the outer end of the tube and comprising a body having a chamber 70 therein in communication with the tube, a perforated tube rotatably carried by the body and having its perforated part located in the chamber, a handle on one end of the tube and means for attaching a nozzle to the 75 other end of the tube.

In testimony whereof I affix my signature.
CHARLES E. LINK.
